UNITED STATES PATENT OFFICE.

PATRICK J. MADDEN, OF CHICAGO, ILLINOIS.

WATER-CLOSET.

SPECIFICATION forming part of Letters Patent No. 550,415, dated November 26, 1895.

Application filed March 31, 1894. Serial No. 505,861. (No model.)

To all whom it may concern:

Be it known that I, PATRICK J. MADDEN, a citizen of the United States, residing at Chicago, in the county of Cook and State of Illinois, have invented certain new and useful Improvements in Water-Closets, of which the following is a specification, reference being had to the accompanying drawings, which are made a part hereof, and in which—

10 Figures 1 and 2 are respectively a side and a rear elevation of the upper portion of the bowl of a water-closet embodying the invention. Fig. 3 is a horizontal section of a portion thereof on a somewhat larger scale, the cutting-plane being indicated by the line 3 3, Fig. 1. Fig. 4 is a horizontal section on a somewhat smaller scale than Fig. 3, but on a similar plane, showing a modification.

The present invention relates to that class 20 of water-closets in which the seat (or lid, or both seat and lid) is attached directly to the bowl; and the object of the invention is to provide an improved attaching device. To this end the invention consists in the features 25 of novelty that are particularly pointed out in the claims hereinafter.

In the drawings, A represents a portion of the bowl, and α an enlargement thereof, which, as shown, takes the form of a heavy rib or 30 flange extending horizontally across its back; but the shape of this enlargement is not an essential feature of the present invention. Its only object is to insure sufficient strength at the points which receive the strain from the 35 attaching devices. It is a mere thickening of the top of the bowl, and in the following specification it will not be treated as a distinct feature.

Referring to Fig. 3, A represents a portion 40 of the bowl, having a socket comprising a branch B, opening at the back of the bowl, and a branch C D, opening at the side thereof and intersecting the branch B. E is a part, hereinafter called an "anchor," located in the branch B, and F is a screw-bolt or similar device occupying the branch C D and passing through an eye formed through the anchor. Preferably that portion of the screw-bolt which occupies the eye of the anchor is 45 threaded and engages corresponding threads 50

in the eye; but I desire to have it understood that in its broadest aspect my invention is not limited to this construction, and in Fig. 4 a different construction is shown. Here the bolt is threaded only at its end, and 55 upon it fits a nut F', which occupies a socket G, which is formed in the back of the bowl and with which the branch D' (corresponding to the branch D of Fig. 3) communicates.

Referring to Fig. 3, H and I represent elastic sleeves or buffers, which fit upon the portions f and f' of the bolt and fill the branch C D. The anchor has a stem J, provided with threads which engage corresponding threads in a socket j, which is formed in the 60 end of a bracket-arm J', the end of which is sufficiently large to span the open end of the socket. As shown in Fig. 4 this bracket bears immediately against the bowl; but as shown in Fig. 3 it bears upon it through the 65 medium of an elastic buffer K. The end of the bracket is provided with a depression j², of somewhat greater diameter than the socket, and in this depression fits the buffer K, which is of greater diameter than the socket, so that 70 its margin rests upon the margin of the socket and is compressed between the bracket and bowl when the bracket is rotated in the proper direction. I desire to have it understood, however, that in its broadest aspect my 75 invention is not limited to these elastic buffers H, I, and K, and in some instances they may, if desired, be dispensed with. They are, however, highly desirable when the bowl is of 80 earthenware, as they make a yielding connection and relieve the bowl of very much of the strain and concussion that would inevitably come upon it if they were omitted, and to 85 provide a more perfect device for attaching the seats or lids to bowls of this class is one 90 of the principal objects of the invention.

The construction above described is duplicated upon opposite sides of the bowl, as shown in Fig. 2. To the seat L are secured a pair of arms M, having at their extremities eyes m, 95 and to the lid N are secured a pair of arms O, having at their extremities eyes o, said arms being so located that the eyes J² of the bracket-arms and the eyes m and o of the arms M and O come together end to end in sets of three, 100

so that a bolt P may be passed through each set, and thus the several arms are hinged together.

What I claim as new, and desire to secure 5 by Letters Patent, is—

1. The combination with a bowl, of a pair of rotatively attached brackets, said brackets being detachable only by rotating them, and a seat hinged to the brackets and normally 10 preventing their rotation, substantially as set forth.

2. The combination with a seat and bowl having a socket, of an anchor secured in said socket, a bracket adapted to bear upon the 15 bowl and having rotative engagement with the anchor, said anchor and bracket having engaging threads, so that by rotating the bracket it may be brought to bear upon the bowl, and a seat hinged to the bracket and preventing 20 its rotation substantially as set forth.

3. The combination with a bowl having two 25 sockets, of two anchors fitting in said sockets, two brackets having rotative engagement with the anchors and adapted to bear upon the bowl, the anchors and brackets having engaging screw threads, so that by rotating the brackets they may be brought to bear upon the bowl and the bowl thereby clamped between them and the anchors, and a seat hinged 30 to the brackets and preventing their further rotation, substantially as set forth.

4. The combination with the seat and bowl, having a socket, of an anchor occupying said 35 socket, a bracket having rotative engagement with the anchor, and adapted to bear upon the bowl, and an elastic buffer arranged between the bracket and bowl, the anchor and bracket having engaging threads, so that by rotating the bracket it may be brought to bear upon the bowl, through the medium of the buffer, 40 substantially as set forth.

5. The combination with the seat and the bowl having a socket, of an anchor occupying said socket, a bracket secured to the an-

chor, and an elastic buffer arranged between 45 the bracket and bowl, the bracket having a depression in which a portion of said buffer fits, substantially as set forth.

6. The combination with the seat and the bowl having a socket with intersecting 50 branches, of an anchor arranged in one branch of said socket and having an eye registering with the second branch, a bolt occupying the second branch of the socket and the eye of the anchor, an elastic buffer arranged between 55 the bolt and the bowl and a bracket secured to the anchor, substantially as set forth.

7. The combination with the seat and the bowl having a socket with intersecting 60 branches, of an anchor arranged in one branch of the socket and having an eye registering with the second branch, a bolt occupying the second branch of the socket and the eye of the anchor, an elastic buffer arranged between 65 the bolt and the bowl, a bracket secured to the anchor, and an elastic buffer arranged between the bracket and the bowl, substantially as set forth.

8. The combination with the seat and the bowl having a socket with intersecting 70 branches, of an anchor arranged in one branch of the socket and having an eye registering with the second branch, a bolt occupying the second branch of the socket and the eye of the anchor, an elastic buffer arranged between 75 the bolt and the bowl so as to allow the bolt a limited lateral movement, a bracket having rotative engagement with the anchor, and an elastic buffer arranged between the bracket and the bowl, the bracket and anchor 80 having engaging threads so that by rotating the bracket it may be brought to bear upon the bowl through the medium of the buffer, substantially as set forth.
